UNITED STATES PATENT OFFICE

GEORGE P. REGAN, OF OAKLAND, CALIFORNIA, ASSIGNOR TO PARKER-REGAN CORPORATION, OF SAN FRANCISCO, CALIFORNIA, A CORPORATION OF NEVADA

MOP HOLDER

Application filed July 17, 1930. Serial No. 468,498.

This invention relates to mops, and more particularly to an improved type of mop and holder which is adapted to serve both as a mop and as a wringer.

5 The object of the present invention is to generally improve and simplify the construction and operation of mop holders; to provide an improved type of mop holder of inexpensive construction which employs 10 means by which the mop may be tightly twisted or wrung without being actually handled by the user; and, further, to provide a mop holder to which the mop may be quickly and readily applied or removed.

15 The mop holder is shown by way of illustration in the accompanying drawing, in which—

Fig. 1 is a perspective view of the same, and

20 Fig. 2 is an enlarged plan view of the mop holder.

Referring to the drawing in detail, A indicates a handle, B a mop holder secured to the lower end of the handle, C a wringer 25 slidably mounted on the handle, and D a mop carried by the holder B and the wringer C.

The mop holder comprises a flattened metal head 2, which terminates in a cylindrical shaped sleeve 3, which is adapted to be slipped 30 over the lower end of the handle and there secured by a pin or rivet such as indicated at 4. Carried by the head member is an elongated loop-shaped mop receiving and securing element which is preferably constructed of heavy wire such as shown at 5. This mop receiving element is secured to the head 2 by bending the metal of the head over the wire as indicated at 6 and there securing 35 it by clinching or pressing the metal tightly about the wire; the wire being secured against turning movement about its longitudinal axis by having an offset formed therein as indicated at 7. One end of the wire is bent to 40 form a loop 8 which carries a catch 9. This catch is in the form of a metal sleeve which is slipped over the end of the wire and secured by crimping or clinching action. The projecting end of the sleeve indicated at 9 is open 45 to permit insertion of a wire arm 10, this arm

forming an extension of a loop indicated at 11.

The wringer indicated at C is identical in construction to the mop holder B, the only difference being that the cylindrical sleeve-like extension indicated at 3a is considerably longer than the sleeve 3 and it is free to slide and turn about the handle A.

Any suitable type of mop cloth may be employed as indicated at D in Fig. 1. Mop cloths of this character are usually provided with loops at opposite ends as indicated at 12 and 14 which are formed by sewing the cloth transversely as indicated by the lines 15. When a mop cloth is to be applied, the wire 60 arms 10 are released with relation to the catches 9 and sprung outwardly as shown in Fig. 2. The loop ends 12 and 14 may thus be slipped over the arms 10 after which they are bent inwardly and brought into engagement with the catches 9. The mop cloth may then be spread out over the arms 10 and the catches 9 so as to lie in an evenly distributed 65 position between the loops 7 and 8.

In actual practice, the wringer member C, 75 to which the upper end of the mop cloth is attached, is slid downwardly on the handle so as to assume a position just above the mop holder B. In this position the mop cloth is doubled up and is in position for use. When 80 it is desired to wring the mop cloth the wringer C is pulled upwardly on the handle as shown in Fig. 1, and either the handle or the sleeve or both may be rotated, thus twisting the mop cloth about the handle and insuring 85 wringing thereof. By merely releasing the wringer C, the mop cloth untwists and the sleeve drops by gravity back to normal operating position.

Mops of this character are in continuous use 90 and as such wear out fairly rapidly. It is accordingly necessary to apply new mop cloths from time to time. This operation is usually more or less complicated with the majority of mops now in use. With a mop 95 holder such as shown in the present instance the operation of either applying or removing the mop cloth is exceedingly simple as it is only necessary to crowd the mop cloth towards the loops 11 and then release the arms 100

10 with relation to the catches 9 when both ends of the mop cloth may be readily removed. The operation of applying a new cloth being just the reverse, no trouble or time is lost in either applying or removing the mop cloth. Furthermore accidental release is prevented due to the catches 9 employed.

15 While certain features of the present invention are more or less specifically described, I wish it understood that various changes may be resorted to within the scope of the appended claims.

20 Having thus described my invention, what I claim and desire to secure by Letters Patent is—

25 1. In a device of the character described a head member, a wire rod having a portion extending transversely of the head, said head having a flanged portion bent over the transverse portion of the rod and clinched to secure the rod, said rod having a kink formed thereon and engaged by the clinched flange to secure the rod against turning movement and endwise movement with relation to the head, a return bend loop formed on each end of the rod, a catch member carried by one loop, and an arm forming an extension of the other loop, the free end of said arm being movable into and out of engagement with the catch.

30 2. In a device of the character described, a head member, a wire rod extending transversely of the head, said head having a flanged portion bent over the rod and clinched to secure the rod, said rod having a kink formed thereon and engaged by the clinched flange to secure the rod against turning movement and endwise movement with relation to the head, a return bend loop formed on each end of the rod, a short arm forming an extension of one loop, a sleeve secured to said arm, said sleeve projecting beyond the end of the arm and terminating in a catch member, and a second arm forming an extension of the other loop and having a free end movable into and out of engagement with the catch member.

35 3. In a device of the character described, a head member, a rod extending transversely of the head member, one edge of said head member being bent over said rod to grip the rod throughout at least one-half of its length, said rod having a bent portion engageable with the head member to prevent relative turning movement between the rod and head member.

GEORGE P. REGAN.
